CIRCUIT CONTROLLING APPARATUS

Joseph F. Frese, Baltimore, Md., assignor to The
Monitor Controller Company, Baltimore, Md.,
a corporation of Maryland

Application October 20, 1945, Serial No. 623,560

15 Claims. (Cl. 200—147)

1

My invention relates particularly to electrical switches and more particularly to high potential switching systems.

One of the objects of my invention is to provide a construction of high potential switch having means for blowing out articulated arcs which may form at the contact breaks of the switches.

Another object of my invention is to provide a construction of high potential switch embodying means for substantially quenching the arc formed at the contact breaks without the necessity of submerging the contacts in oil with the incidental necessity of refilling the oil feeding reservoirs from time to time.

Another object of my invention is to provide a construction of high voltage magnetic blowing out airbreak contactor system having means for substantially extinguishing the arc at the contact break of the switching system.

Still another object of my invention is to provide the construction of an arc cooler for high voltage switching systems arranged immediately adjacent the high voltage contactor for cooling the arc and rapidly quenching the arc at the contact breaks.

A still further object of my invention is to provide a construction of magnetic blowout airbreak contactor system in which a concentrated magnetic field threads the gap between the fixed and movable contactors of the high voltage system with an arc dissipating chamber so associated with the contacts that the arc may be rapidly dissipated.

Other and further objects of my invention reside in the construction and arrangement of a multiple phase high voltage magnetic blowout airbreak contactor system as set forth more fully in the specification hereinafter following by reference to the accompanying drawings, in which:

Figure 1 is a front elevational view of a three-phase high voltage magnetic blowout airbreak contactor system embodying the arrangement of my invention; Figure 2 is a rear elevational view of the contactor system shown in Figure 1; Figure 3 is an enlarged sectional view through one of the high voltage contactors showing the association therewith of the magnetic blowout airbreak system of my invention; Figure 4 is a transverse sectional view taken through one of the magnetic blowout airbreak contactor systems substantially on line 4—4 of Figure 3; Figure 5 is a horizontal sectional view taken on line 5—5 of Figure 3; Figure 6 is a detail view illustrating the manner of detachably securing the individual magnetic blowout systems in position in association with

2

the high potential contactors; Figure 7 is a sectional view taken on the line 7—7 of Figure 6; Figure 8 is a theoretical view showing the association of the airbreak magnetic blowout system with the contactor arranged in a high potential circuit; Figure 9 is a schematic view through the arc cooler showing the separate ionized channel paths established therein; Figure 10 is a theoretical view showing the ionization paths of the arcs; Figure 11 is a theoretical view showing the potential distribution by the adjacent rods in the ionized paths of the arc cooler and Figure 12 is a theoretical view showing the magnetic distribution between the ionized channel paths of the arc cooler.

Referring to the drawings in detail, reference characters 1 and 2 represent end plates of a frame structure which supports the high voltage magnetic blowout airbreak system of my invention. 10 The frame constituted by end plates 1 and 2 has interconnecting metallic bars 3, 4 and 5 extending therethrough. These metallic bars are each covered by heavy insulation tubes such as, for example, a phenol condensation product or other 15 insulation material represented at 3a, 4a and 5a. The tubes of insulation material extend to the washer members 1a and 2a which bear against the end plates 1 and 2, respectively, and serve to mount the bars 3, 4 and 5 rigidly in position between the end frame plates 1 and 2 against the nuts 3b, 4b and 5b. The tubes of insulation material serve as supporting means for the several sections of the high voltage magnetic blowout 20 airbreak contactor system. The contactors are arranged in sections so that a single throw section may be associated with comparable sections in a multiple phase system. In the arrangement shown, my invention is applied to a three-phase high voltage system, but it will be understood that the switching system may be used singly or in any 25 desired multiple combination.

The contactor system is operated by the angularly movable shaft 6 which is connected at one end with the actuator 65 and is journaled at the other end in bracket 72 which is supported at 73 on bar 4. The shaft 6 is covered by a tube of insulation material represented at 9 and around this tube there is clamped the switch arm 10 comprising members 11 and 12 clamped on 30 opposite sides of the tube of insulation material 9 by means of screw members 14. The arm 10 carries the movable contactor 15 which is yieldably supported on the arm by means of block 16 pivotally supported at 17 with respect to section 35 11 of arm 10. The block 16 is maintained under

tension by spring member 18 disposed between the angle member 19 carried by section 11 of arm 19 and the rear extension 29 on the contactor 15. A limiting stop 21 is positioned adjacent the extremity of section 11 of arm 19 and serves as an abutment for block 16 in limiting the forward travel of the contactor 15. Thus, within limits determined by the yieldability of spring 18 and the stop 21 contactor 15 is free to be slightly displaced in the course of its movement into contacting position with the fixed contactor represented at 22.

The fixed contactor 22 has a longitudinal extension thereon constituting a runner 26 which extends upwardly to a position immediately below the arc cooler 27 shown at 26a. The contactor 22 is mounted on the rear of panel member 24 of insulation material and, by suitable support 23 which is fastened to panel 24 by bolt member 25.

The runner 26 is electrically connected through support 23 to connecting member 28 extending therefrom through the panel 24 and serving as an electrical connector to one end 29 of the magnetic blowout coil represented at 30. The other end of the magnetic blowout coil 30, shown at 31, is connected to terminal 32 supported on a bracket 34, a block of insulation material 33 mounted on panel 24. The terminal 32 is connected to the end of bracket 34 to the high voltage supply system. The circuit from the contactor system to high voltage supply source is completed through a flexible conductor 35 which connects a lug 36 secured to the movable contactor 15. The other end of flexible conductor 35 connects to the metallic strip 74 which serves as a support for the connecting terminal means 75. The strip 74 is supported adjacent bar 5 by means of clamp 76 which also supports the block 77 of insulation material which acts to position the plates of insulating material 40 and 41.

Each of the blowout systems includes a pair of magnetic pole pieces represented at 37 and 38 interconnected by the magnetic core 39 on which the magnetic blowout winding 30 is wound. The 45 pole pieces 37 and 38 are formed from thin magnetic laminations and are inturned at right angles at one peripheral edge, as represented at 37a and 38a, and are directed toward each other terminating on opposite sides of the plates of insulation material represented at 40 and 41. The laminations constituting the pole pieces 37 and 38 are each shaped as represented in Figure 3 to provide a recess having peripherally extending edges 37b and 37c terminating in a shoulder recess 37d. The recess 37d imparts sufficient resiliency to the laminations to enable the magnetic core 39 to be introduced in the recess defined edges 37b and 37c to form therewith a magnetic field for this distributing lines of force threading the gap between the contactors 15 and 22. The plates of insulation material 40 and 41 are spaced from each other by bushing members 42 and 43 adjacent the corners thereof through which bolts 44 and 45 pass.

The plates 40 and 41 have the edges thereof, which register immediately adjacent panel 24, connected by bolt members 46 and 47. Bolt members 46 and 47 pass through and project from plate members 40 and 41 and engage the metallic recessed blocks 48 and 49 which extend from the front of the panel 24. The recessed blocks 48 and 49 are secured to the front of panel 24 by bolt members 50 and 51 which pass through angle members 52 and 53. As an en-

closure, open at the front, back, top, and bottom edge, around the contactor system, the plate members are inserted between the pole faces 37a and 38a abutting against the insulated panel 24 and moved to a position in which angle members 52 and 53 engage over the tubes of insulation material 3a and 4a respectively. Bolts 46 and 47 seat within the recesses in the blocks 48 and 49. The recesses in blocks 48 and 49 are tapered or inclined, as represented at 46a and 47a, to enforce tight engagement between the peripheral edges of plate members 40 and 41 and the front of panel 24. An insulated tubular sleeve and spacer member 46b and 47b serves to space the plates 40 and 41 and insulate bolts 46 and 47 from the path of the arc discharge. The sleeve and spacer members 46b and 47b are formed from asbestos to eliminate any danger of burning due to heat and discharge of the arc.

In order to support the magnetic blowout system I provide blocks 54 and 55 between the outside faces of plate members 40 and 41 and the space which is provided between the inturned faces 37a and 38a of the pole pieces and the plate members 40 and 41. The blocks 54 and 55 are secured to the pole pieces 37 and 38 by means of bolts 56 and 57 and are secured to the panel of insulation material at 24 by screw members indicated at 54a and 55a. Intermediate the inner faces of the magnetic pole pieces 37 and 38 and the ends of the support for the magnetic insets 54 and 55 I provide non-ferrous plates 58 and 59 as shown.

The runner 26 extends upwardly behind the front of panel 24 of insulation material in spaced relation thereto and terminates immediately adjacent the arc cooler 27. The arc cooler 27 comprises a sheet of insulation material shown at 60 which is suspended between the plates of insulation material 40 and 41 by insulated pin members 61 and 62 which extend through the plate members 40 and 41 and are provided with spacing collars 61a and 62a to center the plate 60 between plates 40 and 41. It will be observed that plate 60 is shaped to terminate closely adjacent the end of runner 26 at the peripheral face 27a and 27b thereof and is tapered or inclined along edge 27c to allow freedom of movement of the movable contactor 15 as shaft 6 is angularly revolved in opening and closing the contacts constituted by movable contactor 15 and stationary contactor 22. The plate 60, immediately adjacent the peripheries 27a, 27b and 27c thereof, is provided with a multiplicity of spaced non-ferrous metallic plugs shown at 63. These plugs pass through the insulation material 60 and project symmetrically on either side thereof substantially filling the space between the plates of insulation material 40 and 41. The plugs 63 are so spaced that the arc which forms upon the separation of the contactors 15 and 22 may be dissipated by following the magnetic line of force which threads the pole faces 37a and 38a across the gap through the contactors 15 and 22, threading upwardly through the spaced plugs. The charge developed in the arc by being distributed between the multiplicity of plugs may be rapidly dissipated and quenched.

The theory of operation of the airbreak system will be clearly understood from Fig. 8 in which it is shown that the magnetic blowout coil 30 is arranged in series with the high potential supply circuit which may be of the order of 2300 volts 500 amperes at 60 cycles and connected through the movable contactor 15 and

stationary contactor 22 to the load represented generally at 64. This load may, for example, be a motor load or a heating load or other type of high voltage electrical load. I have represented schematically the magnetic actuator which controls the movement of shaft 6 by reference character 65. The magnetic circuit of the actuator 65 is connected through remote control switch 66 with the supply line 67. The magnetic lines of force emanating from the magnetic blowout system 30 are represented generally at 68 directing the arc formed between the contactors 15 and 22 in the direction of the spaced plugs 63 in a curved path represented generally at 78 for dissipation through the chimney-like arc cooler 60.

That is to say, the magnetic poles 31a and 38a project the ionized arc 78 into the labyrinth of short metallic conductors 63 following two or more separate ionized channel paths shown at K1 and K2. Figure 9 is a theoretical view showing the two separate ionized channel paths which are provided between plates 40 and 41 and the sides of the plate 60. The arc travels upwardly through the two channel paths shown at K1 and K2. The terminals of the ionization paths are represented at P1 and P2 at contact 15 and runner 26 in Fig. 10 between which the ionized discharge along the paths 78 takes place. The ionization potential gradients in channel paths K1 and K2 are not identical for each portion of the discharge path although:

$$\int_{P2}^{P1} EK1dl = \int_{P2}^{P1} EK2dl$$

where P1 and P2 designate the opposite terminals; E designates the potential; K1 and K2 designate the channel paths; and dl designates the infinitesimal length of the discharge path.

However, $EK1 = EK2$ for the interval dl for the reason that there is a potential difference on the rod C (plugs 63) between points b1 and b2 in a direction determined by the potential of $Vb1 - Vb2$.

In this way there is a random distribution of the current flow in the many rods C (plugs 63). This introduces a potential of opposite polarity at the points n1 and n2 shown in the theoretical diagram of Fig. 11 due to current $iK1$ in channel K2 which tends to reduce the potential due to the space charge of the current in channel K1 and acts somewhat as a negative grid potential on a space charge in the channel path K1, tending to stop the space charge.

Current will also flow across the insulated barrier M (plate 60) through the conducting rod C1 (plugs 63) and endeavor to proceed to the next adjacent rod. However, the rod C1 will not have the ionization current in the interval m2 since it was reduced in the interval m1 by the previously reversed potential. It can be seen that this arrangement of rods or plugs has a choking off action on the ionized vapor path between P1 and P2 in many portions of the path due to the labyrinth of cross-conductors C (plugs 63).

Figure 12 is a further theoretical diagram illustrating the effect on the ionization filament of current i2. The axial or transverse current in rod Cn produces magnetic field p1 and p2. Current i2 sets up a field p1' and p2'. It will be observed that the current filament i2 is torn apart since p2 and p1' pull the current transversely apart.

Hence, the magnetic fields are of a dispersal

character on the current filaments between the rods C (plugs 63) of the system, tending to stop the flow of current between terminals P1 and P2. This phenomenon results in a wholesale tearing to pieces of the current filaments by magnetic actions as well as by reversed potentials.

Fundamentally, the plan is not to extinguish the arc between two metallic contacts but to divide the arc between many metallic contacts and to extinguish the arc between each metallic contact interacting between each other.

I have shown in Figs. 1, 2 and 5 the provision for mounting the magnetic actuator 65 in close association with the contactor system. The magnetic actuator 65 is mounted upon an individual panel 69 supported at the top 70 thereof on insulated tube 3a and steadied at the bottom 71 thereon on the tubular member 4a. The magnetic actuator may be of any desired construction for imparting angular movement to the shaft 6 in operating the contactor.

The arc-quenching labyrinth is formed by the multiplicity of electrically conductive members 63 spaced one from another and interacting in breaking up the arc into a series of short arcs for extinguishing the arc.

I have shown the separable contactor systems in spaced relation along the supporting bars. Any number of such sections may be arranged along the bars for controlling the power circuits. As heretofore pointed out, the arrangement illustrated is intended for three-phase operation. Inasmuch as each magnetic blowout section and chimney-like arc cooler is of identical construction I have limited the description thereof to one section. It will be seen that the magnetic blowout pole pieces are centrally disposed intermediate the insulated tubular members 3a at the top, and 4a and 5a at the bottom, to provide for maximum insulation of the high potential magnetic blowout winding 30.

There is considerable advantage in the air-break arrangement of my invention as compared to oil quenching systems in that requirements for oil supply and necessity for refilling of oil tanks are entirely eliminated. The magnetic blowout system of my invention is practically permanent in its construction as the parts may be readily replaced from time to time due to the simplicity of its construction.

I have found the construction of the high voltage magnetic blowout airbreak contactor system of my invention highly practical for production and successful in use. I realize, however, that modifications in the construction and arrangement of parts of the system of my invention may be made, and I desire that it be understood that no limitations upon my invention are intended other than may be imposed by the scope of the appended claims.

What I claim and desire to secure by Letters Patent of the United States is as follows:

1. A high voltage switch including a housing of insulation material, a barrier of insulation material extending intermediate the sides of said housing, a pair of contactors within said housing, a magnetic system adjacent said housing comprising a magnetic blowout winding and magnetic pole pieces extending therefrom for establishing a magnetic field transverse to said contactors both above and below said contactors for forming separate ionized channel paths above and below said contactors, a labyrinth of short metallic conductors supported by said barrier and pro-

jecting on opposite sides thereof and terminating adjacent the interior walls of said housing and disposed in separate channel paths adjacent said contactors, said short metallic conductors being disposed both above and below said contactors in the magnetic field transverse to said contactors and above and below a substantially medial line passing transversely through said blowout winding and establishing ionization potential gradients in each channel path according to the equation

$$\frac{P_1}{E K_1 d l} = \frac{P_2}{E K_2 d l}$$

where P_1 and P_2 designate the opposite terminals of the ionization paths; E designates the potential; K_1 and K_2 designate the channel paths; and dl designates the infinitesimal length of the discharge path and a panel of insulation material extending in a plane normal to the plane of said barrier for separating said magnetic blowout winding from said contactors and labyrinth.

2. In a high voltage switch, a fixed contactor, a movable contactor coacting therewith, an insulated housing surrounding said contactors and open at the top and bottom thereof, an arm carrying said movable contactor and angularly shiftable within said housing for making and breaking electrical connections between said contactors, an arc runner connected with said fixed contactor and extending upwardly through said housing, a barrier of insulation material supported in spaced relation to the interior walls of said housing and projecting both above and below said contactors and said arc runner, spaced conductive members carried by said barrier and distributed both above and below said contactors and said runner and terminating adjacent the interior walls of said insulated housing, a magnetic blowout winding, magnetic means excited by said winding for directing the arc discharge at said contactors into said spaced conductive members, and inducing into said members currents establishing individual magnetic fields each operating to dissipate the arc discharge, said magnetic blowout winding and said magnetic means associated therewith being located on a substantially medial line extending transversely through said barrier, and a panel of insulation material forming part of said housing and extending normal to said barrier and separating said magnetic blowout winding from said contactors.

3. In a high voltage switch, a fixed contactor, a movable contactor coacting therewith, an insulated housing surrounding said contactors and open at the top and bottom thereof, an arm carrying said movable contactor and angularly shiftable within said housing for making and breaking electrical connections between said contactors, an arc runner connected with said fixed contactor and extending upwardly through said housing, a plate member of insulation material extending through said housing in spaced relation to the interior walls thereof and extending both above and below said arc runner and above and below said contactors, means carried by said plate member above and below said arc runner and above and below said contactors for dissipating the arc discharge at said contactors, a magnetic blowout winding, magnetic means excited by said winding and having pole pieces extending on opposite sides of the exterior walls of said housing with pole faces projecting therefrom in a direction normal to said pole pieces and directing magnetic lines of force through said means car-

ried by said plate member and through the area adjacent said contactors and runner for directing the arc discharge at said contactors and runner through said means, said magnetic blowout winding and said magnetic means excited thereby being located on a substantially medial line extending transversely through plate member and a panel of insulation material forming part of said housing separating said magnetic blowout winding from said contactors, said arc runner and said means.

4. In a high voltage switch, a fixed contactor, a movable contactor coacting therewith, an insulated housing surrounding said contactors and open at the top and bottom thereof, an arm carrying said movable contactor and angularly shiftable within said housing for making and breaking electrical connections between said contactors, an arc runner connected with said fixed contactor and extending upwardly through said housing, a plate of insulation material centrally disposed within said housing and spaced from the interior walls of said housing and aligned with said runner, said plate having the edge adjacent said runner extending in an inclined direction for allowing angular movement of said arm within said housing, electrically conductive means carried by said plate immediately adjacent the inclined edge thereof, a magnetic blowout winding, magnetic means excited by said winding and disposed transversely of said contactors and adjacent the inclined edge of said plate for blowing out the arc formed therebetween and directing the arc through said electrically conductive means carried by said plate, said magnetic blowout winding and said magnetic means excited thereby being located on a substantially medial line extending transversely through said plate and the electrically conductive means carried thereby and a panel of insulation material forming part of said housing and separating said blowout winding from said contactors and arc runner.

5. In a high voltage switch, a fixed contactor, a movable contactor coacting therewith, an insulated housing surrounding said contactors and open at the top and bottom thereof, an arm carrying said movable contactor and angularly shiftable within said housing for making and breaking electrical connections between said contactors, an arc runner connected with said fixed contactor and extending upwardly through said housing, a plate of insulation material extending in spaced parallel relation with respect to the interior walls of said housing and disposed adjacent said arc runner, plugs of a conductive material supported by said plate at spaced intervals and projecting symmetrically on each side thereof and terminating adjacent the interior walls of said housing for forming spaced discharge surfaces, a magnetic blowout winding, magnetic means excited by said magnetic blowout winding for establishing a magnetic field transverse to said contactors and through the area of said plugs for directing the arc discharge from said contactors in separately spaced channels between the opposite projecting sides of said plugs for progressive discharge therebetween, said magnetic blowout winding and said magnetic means excited thereby being located on a substantially medial line extending transversely through said plate and the plugs carried thereby, and a panel of insulation material forming part of said housing and extending normal to said plate for separating said blowout winding from said contactors, arc runner and plugs.

6. In a high voltage switch, a fixed contactor,

a movable contactor coacting therewith, an insulated housing surrounding said contactors and open at the top and bottom thereof, an arm carrying said movable contactor and angularly shiftable within said housing for making and breaking electrical connections between said contactors, an arc runner connected with said fixed contactor and extending upwardly through said housing, a plate of insulation material centrally aligned with said runner within said housing and equally spaced from the interior walls of said housing and recessed to allow angular displacement of said arm, a plurality of plugs of electrically conducting material mounted at spaced intervals in said plate and projecting equally on opposite sides thereof and terminating adjacent the interior walls of said housing for forming two arc dissipating paths within said housing, a magnetic blowout winding, magnetic means excited by said winding for establishing a magnetic field throughout the area of said contactors, said runner, and said plugs, for directing arc discharge at said contactors through the two arc dissipating paths within said housing, said magnetic blowout winding and said magnetic means excited thereby being located on a substantially medial line extending transversely through said plate and the plugs carried thereby and a panel of insulation material forming part of said housing and extending normal to said plate for separating said blowout winding from said contactors, arc runner and plugs.

7. In a high voltage switch, a frame, an insulated panel structure detachably supported on said frame, a fixed contactor carried by the rear of said panel structure, an angularly movable arm operative adjacent the rear of said panel structure, a movable contactor carried by said angularly movable arm for establishing or breaking electrical connection with said fixed contactor, bracket members extending rearwardly from said panel structure, a housing of insulation material detachably mounted in said bracket member behind said insulated panel structure and surrounding said contactors, means carried by said housing adjacent said contactors comprising a barrier of insulation material disposed centrally of said housing and projecting beyond each end of said contactors, spaced metallic members distributed over said barrier beyond each end of said contactors and projecting symmetrically on each side of said barrier, a magnetic blowout winding mounted on the front of said panel structure and magnetic means excited by said blowout winding and extending rearwardly from said panel toward said housing for magnetically directing arcs formed at said contactors into said spaced metallic members, said magnetic blowout winding and said magnetic means excited thereby being located on a substantially medial line extending transversely through said barrier and the spaced metallic members distributed thereover, said panel of insulation material separating said blowout winding from said contactors and said metallic members.

8. In a high voltage switch, a frame, an insulated panel structure, brackets extending from the front of said panel structure and engageable with said frame, a fixed contactor carried by the rear of said panel structure, an angularly movable arm operative adjacent the rear of said panel structure, a movable contactor carried by said angularly movable arm for establishing or breaking electrical connection with said fixed contactor, brackets extending from the rear of said panel

structure, a housing of insulation material detachably mounted in said last mentioned brackets behind said insulated panel structure and surrounding said contactors, an insulated plate mounted within said housing and recessed adjacent said contactors and extending both above and below said contactors, a plurality of spaced metallic plugs carried by said insulated plate and distributed both above and below said contactors, a magnetic blowout system including a magnetic blowout winding and magnetic pole pieces, said blowout winding being mounted on the front of said panel structure and said magnetic pole pieces extending rearwardly therefrom for magnetically directing arcs formed at said contactors into said spaced metallic plugs, said magnetic blowout winding and said magnetic pole pieces being located on a substantially medial line extending transversely through said insulated plate and the spaced metallic plugs carried thereby, said insulated panel structure separating said magnetic blowout winding from said contactors and said plugs.

9. In a high voltage, an insulated panel structure, a fixed contactor carried by said panel structure, an angularly movable arm operative adjacent one side of said panel structure, a movable contactor carried by said angularly movable arm for establishing or breaking electrical connection with said fixed contactor, bracket members projecting rearwardly of said panel structure, a housing of insulation material detachably mounted in said bracket members behind said insulated panel structure and surrounding said contactors, a plate of insulation material disposed within said housing and spaced from the interior walls thereof in alignment with said contactors, plugs of electrically conductive non-ferrous material extending through said plate at spaced intervals and projecting on opposite sides thereof and terminating adjacent the interior walls of said housing for forming arc discharge surfaces intermediate the sides of said plate and the interior walls of said housing, a magnetic blowout winding disposed at the front of said panel structure and magnetic means excited by said blowout winding and extending rearwardly therefrom behind said panel structure for establishing a magnetic field transverse to said contactors for directing arcs formed at said contactors through said arc discharge surfaces, said magnetic blowout winding, and the magnetic means excited thereby being located on a substantially medial line extending transversely through said plate and the plugs carried thereby, said panel structure insulatingly separating said blowout winding from said contactors and plugs.

10. In a switching system, a frame structure, an angularly movable shaft journaled in said frame structure, an arm carried by said angularly movable shaft, a movable contactor carried by said arm, an insulated panel member supported by said frame structure in alignment with said arm, a fixed contactor mounted on the rear of said panel member in the path of movement of the movable contactor, an arc suppressing housing detachably supported on said panel member and surrounding said contactors, a plate member of insulation material extending through said arc suppressing housing intermediate the opposite interior walls thereof and recessed to allow displacement of the associated arm and movable contactor carried thereby, spaced conductive members carried by said plate mem-

ber in positions located both above and below said contactors and terminating adjacent the opposite interior walls of said housing in the path of the arc incident to opening said fixed and movable contactors, a magnetic blowout winding disposed adjacent the front of said panel member, and magnetic means excited by said magnetic blowout winding and extending rearwardly therefrom for directing the arcs from said contactors into said spaced conductive members on said plate member, said panel member separating said blowout winding from said contactors and spaced conductive members.

11. In a switching system, a frame structure, an angularly movable shaft journaled in said frame structure, an arm carried by said angularly movable shaft, a movable contactor carried by said arm, an insulated panel member detachably mounted on said frame structure in alignment with said arm, a fixed contactor carried by the rear of said panel member in the path of movement of the movable contactor, a housing of insulation material detachably supported adjacent said panel member and surrounding the contactors adjacent thereto, a magnetic blowout coil individual to said coating contactors, magnetic pole members extending from said coil in coating relation to the associated contactors, panel and housing, a barrier of insulation material supported by said housing in a position intermediate the interior walls thereof and extending above and below said contactors, a multiplicity of spaced metallic conductors extending transversely through said barrier and supported thereby and terminating adjacent the opposite interior walls of said housing and forming separate arc dissipating paths on each side of said barrier extending both above and below said contactors, said insulated panel member being interposed between the magnetic blowout coil and the associated contactors.

12. In a high voltage switch, a housing of insulation material, a barrier of insulation material extending intermediate the sides of said housing, a pair of make and break contactors within said housing, a magnetic means including a magnetic blowout winding and magnetic pole pieces extending therefrom for establishing a multiplicity of separate ionized channel paths disposed adjacent said contactors and extending both above and below said contactors, said magnetic means operating to maintain said multiple channel ionized paths in a continuous state of ionization, a labyrinth of short metallic conductors supported by said barrier and projecting on opposite sides thereof and terminating adjacent the interior walls of said housing and disposed in each of said paths and operating to provide a multiplicity of electrically conductive paths each establishing magnetic fields opposing the adjacent ionized channel paths, said magnetic blowout winding and the magnetic means associated therewith being located on a substantially medial line extending transversely through said barrier and the labyrinth of short metallic conductors carried thereby, and a panel of insulation material extending substantially parallel to said short metallic conductors and interposed between said magnetic blowout winding and said labyrinth.

13. In a high voltage switch, a housing of insulation material, a barrier of insulation material extending intermediate the sides of said housing, a pair of contactors within said housing,

10 a labyrinth of short metallic conductors supported by said barrier and projecting on opposite sides thereof and terminating adjacent the interior walls of said housing and disposed in each of said paths and extending both above and below said contactors, magnetic means including a magnetic blowout winding and magnetic pole pieces extending therefrom for establishing a magnetic field transverse to said contactors and extending through said labyrinth of short metallic conductors above and below said contactors for inducing in said conductors a current flow for establishing magnetic fields operating to oppose the maintenance of arcs through each of the ionized channel paths, said magnetic blowout winding and magnetic pole pieces extending therefrom being located on a substantially medial line projecting transversely through said barrier and the labyrinth of short metallic conductors carrier thereby, and a panel of insulation material extending substantially parallel to the axis of said blowout winding and interposed between said blowout winding and said labyrinth.

15 14. A high voltage switch including a housing of insulation material, a barrier of insulation material extending intermediate the sides of said housing, a pair of contactors within said housing, a magnetic system adjacent said housing including a magnetic blowout winding and magnetic pole pieces extending therefrom for establishing a magnetic field transverse to said contactors both above and below said contactors for forming separate ionized channel paths above and below said contactors, a labyrinth of short metallic conductors supported by said barrier and projecting on opposite sides thereof and terminating adjacent the interior walls of said housing and disposed in separate channel paths adjacent said contactors, said short metallic conductors being disposed both above and below said contactors in the magnetic field transverse to said contactors and operating to establish opposite magnetic fields at successive distances from said contactors tending to suppress arcs from following the ionized channel paths through said labyrinth of short metallic conductors for suppressing and stopping the arc formed at the break of said contactors, said magnetic blowout winding and the magnetic pole pieces extending therefrom being located on a substantially medial line projecting transversely through said barrier and the labyrinth of short metallic conductors supported thereby, and a panel of insulation material extending in a plane substantially parallel to the axis of said blowout winding and beyond the opposite ends of said blowout winding in a path interposed between said labyrinth and said blowout winding.

20 15. A high voltage switch comprising two main contacts, a housing of insulation material substantially surrounding said contacts, a barrier of insulation material extending intermediate the sides of said housing in opposite directions with respect to said contacts, an arc-quenching labyrinth supported by said barrier and extending on opposite sides thereof to positions adjacent the interior walls of said housing adjacent said contacts, and extending in opposite directions from said contacts, and a magnetic deflection unit including a blowout winding and a pair of pole pieces extending therefrom in a position on opposite sides of said contacts for deflecting arcs from said contacts in opposite directions into said arc-quenching labyrinth,

said blowout winding and the pair of pole pieces extending therefrom being located on a substantially medial line projecting transversely through said barrier and the arc-quenching labyrinth carried thereby, and a panel of insulation material extending in a plane substantially parallel with the axis of said blowout winding and beyond the ends thereof and between said pole pieces in a path interposed between said blowout winding and said contacts and arc-quenching labyrinth.
